UNITED STATES PATENT OFFICE.

IRA W. HOLLETT, OF CHICAGO, ILLINOIS.

PAPER PAIL OR BOX.

SPECIFICATION forming part of Letters Patent No. 279,244, dated June 12, 1883.

Application filed February 2, 1883. (Model.)

To all whom it may concern:

Be it known that I, IRA W. HOLLETT, a citizen of the United States, residing at Chicago, in the county of Cook and State of Illinois, 5 have invented certain new and useful Improvements in Paper Pails or Boxes, of which the following is a specification, reference being had to the accompanying drawings, illustrating the improvements, in which—

10 Figure 1 is a perspective view of the pail or box in form as manufactured, with cover and bail attached. Fig. 2 represents a vertical section of the pail and cover. Fig. 3 represents the plan of the blank; Fig. 4, paper folded and 15 clamped as it appears in process of manufacture.

The object of my invention is to provide a 20 cheap and efficient pail or box for the purpose of holding and transporting liquid, semi-liquid, 25 and other substances; and its nature consists in the improved construction and combination of parts hereinafter described and claimed as new.

In the drawings, A indicates the blank; E, 25 the bail; B, the metal bindings; C, the cover; D, the body of the paper pail or box; G, cuts in pail through which to insert tongues of cover; h and h', edges of the paper, which, when folded, 30 form top of pail; i and i', edges of paper, which, when folded and bound together, form joints in the sides of the pail; j, line on which paper is to be folded in the process of manufacture.

In practice the paper is cut by suitable mechanism into blanks of uniform size and shape, 35 as represented in Fig. 3, though I do not limit myself to the particular angles represented by h i, h' i', i j, and i' j and their corresponding opposites. They may be acute, obtuse, or right, according to the shape of pail desired. The 40 paper is then folded on the line j, so as to bring together the edges, (represented on one side of the paper by i i'), which are then bound together by the metal clamps B, so as to form liquid proof or tight seams, the metal clamps 45 extending above the edges h h', so as to form ears, as represented in Figs. 2 and 3, which are then pierced in order to insert the metal bail E; but I do not limit the other parts of my invention to a pail having a bail, as for many 50 purposes the bail may be omitted, in which case the clamps would not extend beyond the line h h'; nor do I limit myself to clamps ex-

tending simply to the line j. They may be extended beyond this line, so that when the corner (represented by i i' j and its corresponding opposite) are turned in, as hereinafter described, the metal clamps will meet or lap each other a short distance under the bottom of the pail, so as to be clamped or soldered together. 55

The edges h and h' are then bound (separate) with metal B, though I do not limit myself to binding the whole of these upper edges. For pails designed to hold or transport many substances, a binding covering but a portion of these edges is sufficient. The apertures indicated by G are then cut in the paper on or near the lines h and h', as represented in Figs. 3 and 4. I next place the pail, which so far has retained the shape of a sack, over a former and turn in the corner i i' j and its corresponding 60 opposite, so as to form the bottom of the bucket, (represented in Figs. 1 and 2;) but I do not limit the other parts of my invention to a pail having the bottom formed by turning the corners in. They may be turned out or cut off, and 65 the apertures thus formed closed by metal clamps or cement. Neither is it necessary to employ a former in changing the shape from that of a sack to a pail. It can be done by hand simply. The metal bail E is then attached to the metal ears by being inserted 70 through the holes pierced therein, as above described; but, as above stated, I do not limit the other parts of my invention to a pail having a bail, as for many purposes the bail may 75 be omitted, and in pails designed for many purposes I prefer a bail of ribbon, or handle of some similar material, which I can attach to the bucket by clamping the ends of the same 80 into the metal bindings or ribs which secure 85 the edges i i' and their corresponding opposites.

My cover I manufacture from suitable paper or pasteboard of size and shape to fit the interior of the pail on the line between the apertures G, and I make this cover a little longer than the distance between these apertures, so as to form a spring-cover; but I do not limit the other parts of my invention to a pail having this cover, as for many purposes I prefer 90 to use some other, and for others no cover is desirable. 95

In my pail the use of cemented joints and 100 interior folds are avoided, while the formation

of the bottom by turning the corners in under, so as to elevate the bottom from the surface on which the pail rests, must prove of advantage in pails designed for the purpose of holding or 5 transporting liquid or semi-liquid substances.

This pail can also be used as a box or basket, and I believe it will prove especially desirable for the purpose of transporting fruits and vegetables, as its small cost allows of its being destroyed after once used, and the simplicity of its formation into a bucket or box after being manufactured in the shape of a sack enables me to ship in small space large numbers packed flat to such place as they are desired 10 for use.

I am aware that metal bindings and ribs have been used on buckets in some respects similar to mine; but in these the mode of securing the metal to the paper is different, and 15 the metal bindings serve but a portion of the purpose accomplished by mine.

In buckets designed to be carried by a handle the plan of attaching this to the same metal which extends the length of the sides and beneath the bottom of the pail adds greatly to 25 the strength of the same.

I claim as new and desire to secure by Letters Patent—

1. As an improved article of manufacture, a paper pail or box having bottom formed with 30 turned ends or corners held in position by the metal binding B, substantially as set forth.

2. In combination with the body A, the binding-ribs B, having their ends extending beyond the paper body and perforated, whereby 35 the ribs serve the double purpose of binding the edges of the sheet forming the body and of being bail-ears, substantially as specified.

IRA W. HOLLETT.
